NITROPARAFFIN SOLVENT PROCESS FOR
MAKING OLEFIN NITROSOCHLORIDES

Carl Bordenea and Wilbur A. Lazier, Birmingham, Ala., assignors to Food Machinery and Chemical Corporation, a corporation of Delaware

No Drawing Application March 25, 1947,
Serial No. 737,102

5 Claims. (Cl. 260—647)

1

This invention relates to a new and improved process for converting olefins to their nitrosochlorides.

Olefins have heretofore been converted to their nitrosochlorides by dissolving them in solvents such as alcohols and organic acids and passing nitrosyl chloride through the solution. The yields obtained by these prior art processes are, however, unsatisfactory, and vary widely with slight changes in the operating conditions.

It is an object of this invention to convert olefins to their nitrosochlorides by a new and improved process which produces high yields of the desired end product. A further object is to produce these compounds by a process which may be controlled readily and which is simple and economical. Additional objects will become apparent from a consideration of the following description and claims.

These objects are attained in accordance with our present invention, which involves the use of nitroparaffins as solvents for the olefins undergoing reaction. In a more restricted sense our invention is directed to the employment of nitroparaffins having from one to eight carbon atoms as solvents in the reaction between olefins and nitrosyl chloride. In a still more limited sense this invention is concerned with a process wherein olefins, particularly cyclic olefins, and preferably those of the terpene group, are dissolved in a nitroparaffin containing from one to four carbon atoms, after which nitrosyl chloride is passed through the solution. One of the preferred embodiments of this invention involves carrying on the foregoing reaction while maintaining the olefin-nitroparaffin solution at low temperatures, advisably below -10° C. and preferably in the neighborhood of -35° C. for those nitroparaffins which are liquid at these temperatures.

The invention may be more readily understood by a consideration of the following illustrative examples:

Example 1

Over a 1 hour period, 44 g. of nitrosyl chloride was bubbled into a mixture of 100 g. of d-limonene in 200 cc. of nitromethane, maintained between -25° C. and -30° C. The mixture was stirred throughout the period and for an additional 0.25 hour at the above temperature. It was filtered and the precipitate washed with approximately 200 cc. of cold ether. The solid nitrosochloride weighed 64 g., representing a 43 per cent conversion of the d-limonene.

It is to be noted that when the same procedure was followed and a temperature range of $+5^{\circ}$ C.

2

to $+7^{\circ}$ C. was employed, only 52 g. of d-limonene nitrosochloride was obtained, representing a 35 per cent conversion of the limonene.

Example 2

Over a period of 1 hour, 20 g. of nitrosyl chloride was bubbled into a mixture of 46 g. of d-limonene in 100 cc. of nitroethane, maintained between -40° C. and -50° C. The mixture was stirred throughout this period and for an additional 2.5 hours while it was held within the above temperature range. The solid d-limonene nitrosochloride was isolated by filtration, washed with 200 cc. of cold ether, and air-dried; its weight was 26 g., representing a 38 per cent conversion of the d-limonene.

Whereas, in the above examples it has been shown that conversion of d-limonene to its nitrosochloride is obtained in certain solvents, it should be noted that at temperatures of 0° C. or below the reaction apparently does not occur in carbon tetrachloride, carbon disulfide, ethyl acetate, benzene, and ether in the absence of highly polar substances. In methyl, ethyl, and butyl alcohols conversions under 25 per cent have been obtained.

In the above examples in place of the nitromethane and nitroethane solvent there may be employed nitropropane, nitrobutane, nitropentane, nitroheptane, or nitrooctane, with satisfactory results. Likewise, isomers, as well as mixtures of such solvents, may be used. In the same manner the nitro group may be substituted on any of the various possible positions in the alkane radical. It is also contemplated that higher members of the nitroalkane series may be employed, although for optimum results we prefer to use nitroalkanes having no more than eight carbon atoms in the molecule, and preferably from one to four carbon atoms.

It is to be understood that the conditions of reaction set forth in the foregoing examples may be varied considerably without departing from the scope of this invention. For example, the relative amount of the reactants may be varied substantially and the temperature and time of reaction may likewise be varied considerably. As a general rule, it is preferred to use temperatures below -10° C. and preferably in the neighborhood of -35° C. for those nitroparaffins which are liquid at these temperatures. The manner in which the olefin-nitroalkane solution is maintained at these temperatures may be varied considerably in accordance with well-known refrigeration technique.

This invention is applicable to the conversion of olefins generally to their corresponding nitrosochlorides by treatment with nitrosyl chloride. The olefins may be either cyclic or acyclic in nature. A representative group of cyclic olefins is, for example, cyclohexene, methyl cyclohexene, 8,9-dihydrolimonene, 1-limonene, dipentene, α -pinene, β -pinene, and the like. A representative group of acyclic olefins is, for example, octene-1, octene-2, styrene, stilbene, hexadecene, octadecene, and the like.

It is to be understood that mixtures of one or more olefins may be treated in accordance with this invention. This is particularly desirable in the case of those olefins which are difficult to separate from their homologs, wherein the employment of a mixture substantially reduces the cost of the operation.

While this invention broadly contemplates the treatment of cyclic and acyclic olefins, it is to be understood that it is particularly adapted to the conversion of cyclic olefins, especially those of the terpene class, to their corresponding nitrosochlorides. The preferred embodiment of this invention, as is evident from the above examples, is the treatment of limonene, preferably d-limonene.

By means of the present invention a simple and economical process for the production of nitrosochlorides is rendered available. This is an important reaction, but heretofore, so far as we are aware, the yields, and therefore the expense of the operation, was unsatisfactory. We have now found that this difficulty is in large measure attributable to the use of an inefficient solvent system. The solvent system of our invention, particularly in conjunction with the employment of low temperatures, avoids these and other disadvantages inherent in the prior art.

As many apparently widely different embodiments of this invention may be made without departing from the spirit and scope hereof, it is to be understood that the invention is not limited to the specific embodiments hereof except as defined in the appended claims.

We claim:

1. A process which comprises dissolving an ole-

fin having at least six carbon atoms in a nitroparaffin having from one to eight carbon atoms, passing nitrosyl chloride therethrough at a temperature below 0° C., and thereafter separating the resulting nitrosochloride therefrom.

2. A process which comprises dissolving a terpene olefin in a nitroparaffin having from one to eight carbon atoms, maintaining the solution at a temperature below -10° C., passing nitrosyl chloride therethrough, and thereafter separating the resulting nitrosochloride therefrom.

3. A process which comprises dissolving limonene in a nitroparaffin having from one to four carbon atoms, maintaining the solution at a temperature below -10° C., passing nitrosyl chloride therethrough, and thereafter separating the resulting limonene nitrosochloride therefrom.

4. A process which comprises dissolving d-limonene in nitromethane, maintaining the solution at a temperature below -10° C., passing nitrosyl chloride therethrough, and thereafter separating the resulting d-limonene nitrosochloride therefrom.

5. A process which comprises dissolving d-limonene in nitroethane, maintaining the solution at a temperature below -10° C., passing nitrosyl chloride therethrough, and thereafter separating the resulting d-limonene nitrosochloride therefrom.
